UNITED STATES PATENT OFFICE.

HENRY HOLCROFT, OF MEDIA, PENNSYLVANIA.

BURGLAR-ALARM.

SPECIFICATION forming part of Letters Patent No. 240,024, dated April 12, 1881.

Application filed October 6, 1880. (Model.)

To all whom it may concern:

Be it known that I, HENRY HOLCROFT, of Media, Delaware county, and State of Pennsylvania, have invented a new and useful Improvement in Burglar-Alarms, of which the following is a specification.

My invention relates to alarms which may be attached to doors, windows, or other places where alarms may be desired in case of an attempted theft, burglary, or intrusion; and it consists in the combination and arrangement of a metal frame provided with an arm, in the end of which is a small circular recess for holding one or more paper torpedoes, a spindle to which is connected an arm having at its extreme end a hammer, which is operated by a pin, retaining-catch, and coiled spring, as will be hereinafter described, referring to the annexed drawings, making a part of this specification, in which—

Figure 1 is a view of my improved alarm suspended on a door-knob ready for action. Fig. 2 is a view of the same after having been cast off the knob and giving the alarm. Fig. 3 is a view of the alarm detached from the suspending-cord. The other views are separated and detached parts of the alarm, and indicated by letters of reference.

Similar letters refer to similar parts throughout the several views.

The main part of the machine is represented by the arm A, hub G, and spindle J, which should be made of metal. Cast-iron will do. In the arm A is recessed a small recess, d, about one-eighth of an inch deep, and of diameter a little less than the paper torpedoes to be used. In the hub G is drilled a hole for the free working of the spindle S. At the top of the hub G is a notch, R. On the spindle J is placed a coiled spring. One end is fastened to spindle J, and the free end rests on the arm a. The spindle S is provided with an eye, to

which is attached the cord D. In this spindle is also a small pin, b, and on the arm a is the hammer C. These parts may be made of cast-iron, with the exception of the spring B, which should be of steel or brass spring-wire.

The manner of using my improved alarm is as follows: The pin b is turned and pressed into the catch R and held by friction, which elevates the hammer C, as shown in Fig. 1. One or more paper torpedoes (such as used by children in toy pistols) are pressed by the finger in the recess d. The free end of the cord D is looped around the knob-shank, and the hook E is hung on the knob F, thus suspending the alarm, as shown in Fig. 1. If the knob F be turned from the outside of the door the hook E will be thrown off the knob, and as the alarm falls it will draw tight the slack cord, release the pin b from the catch R, and the coiled spring B will force the hammer C against the torpedoes placed in the recess d, explode them, and give the alarm.

It is obvious that my invention may be suspended on any suitable support, and the hook E connected by a string to a window-sash, shutter, or other object, so that it may be thrown off by moving such object and give the alarm, the same as above described.

I am aware that it is not new to suspend the alarm on a door-knob, nor to make an alarm by exploding torpedoes. These I do not claim; but

I claim as my invention—

The combination and arrangement of hook E, suspending-cord D, spindle S, pin b, catch R, coiled spring B, arm a, hammer C, and recess d, as shown, described, and for the purpose specified.

H. HOLCROFT.
